COMBINED RECORDING MACHINE CASING AND COVER

Heinz Huebner, Fuerth, Bavaria, Germany, assignor to Grundig Elektro-Mechanische Versuchsaustalt, Fuerth,
Bavaria, Germany, a German company

Filed Dec. 1, 1959, Ser. No. 58,523

Term of patent 14 years

(Cl. D26—14)

Fig. 1 is a front perspective view of a combined recording machine casing and cover, showing my new design;

Fig. 2 is a front elevational view; and

Fig. 3 is an end elevational view, the opposite end being substantially a mirror image thereof.

I claim:

The ornamental design for a combined recording machine casing and cover, as shown and described.
